UNITED STATES PATENT OFFICE.

VAINO W. MALMSTROM, OF BAYONNE, NEW JERSEY.

PUMP, COMPRESSOR, OR THE LIKE.

Application filed May 19, 1926. Serial No. 110,275.

This invention relates to improvements in apparatus for the pumping of fluids, either liquid, air or gaseous, and which may be utilized as a pump or compressor in the 5 preferred instance, but which by a reversal of the fluid when the same is acting as a pressure medium may provide a motor or prime mover for operating any suitable mechanism.

10 The primary object of this invention is the provision of an improved mechanism, such as a pump, compressor or the like, which embodies a novel rotary pumping unit having a plurality of vanes adapted to 15 operate in novel manner with certain stationary parts of the mechanism for effecting a continuous and well regulated suction or flow of fluid through the housing.

A further object of this invention is the 20 provision of an improved rotary type of pump or compressor, comprising a balanced arrangement of rotary pumping units by which to most effectively eliminate end thrust upon a rotary shaft and bearings.

25 A further object of this invention is the provision of a rotary type of pump, compressor, or motor, embodying a pair of shafts upon each of which are supported a pair of rotors, the rotors of one shaft cooperating 30 in an intermeshing relation with the rotors of the other shaft; free of contact with each other and cooperating in a novel relation with stationary details of the housing, to prevent leak of the operating medium or the 35 medium being pumped.

A further object of this invention is the 40 provision of a rotary type of pump or compressor, embodying a compact arrangement by reason of the novel formation of rotor units.

Other objects and advantages of this invention will be apparent during the course of the following detailed description.

45 In the accompanying drawings, forming a part of this specification, and wherein similar reference characters designate corresponding parts throughout the several views,

Figure 1 is a vertical sectional view taken longitudinally through the improved device.

50 Figure 2 is a sectional view taken substantially on the line 2-2 of Figure 1 thru one of the shafts of the improved device, showing the details thereof.

55 Figure 3 is a horizontal sectional view taken thru the improved device, along an upper shaft, substantially on the line 3-3

of Figure 1, showing cooperating housing and rotor details.

Figure 4 is a sectional view taken substantially on the line 4-4 of Figure 3. 60

Figure 5 is a sectional view similar to Figure 4, showing a different arrangement of the rotor vanes than that illustrated in Figure 4.

Figures 6, 7 and 8 are sectional views 65 taken substantially on their respective lines in Figure 1 of the drawings.

Figure 9 is a perspective view of a supporting core embodied as a part of the improved device. 70

Figure 10 is a perspective view of a rotor unit.

Figure 11 is a perspective view of another rotor unit of the improved device.

Figure 12 is a perspective view of supporting core different than that illustrated in Figure 9. 75

Figure 13 is a perspective view of a sealing ring construction embodied as part of the improved apparatus. 80

Fig. 14 is an enlarged sectional view taken thru a location of attachment of the sealing ring upon the rotor housing.

In the drawings, wherein for the purpose of illustration is shown only a preferred embodiment of the invention, the letter A 85 may generally designate the improved pump, compressor, or motor, as the case may be, and depending upon the use to which the same may be put, which may comprise a stationary housing B, rotatably supporting upper and lower shafts C and D. The upper shaft C preferably rotatably supports rotor units E and F in the housing B, for pumping cooperation with the units G and H 95 respectively, which are carried by the lower shaft D.

While in the specification and claims of this application a pump, compressor, or motor may be specifically referred to, it is 100 to be distinctly understood that such terms are used only for the purpose of giving nomenclature to the parts, and are not to be construed in a limiting sense, since the improved apparatus may be utilized for the 105 purpose of pumping liquids as well as air or gases; may be used as a compressor for fluids; or may be used as a motor, operated by any suitable fluid medium.

The housing B preferably comprises a 110 main body portion 20, having top and bottom arcuated walls 21 and 22, struck from

the centers on which the shafts C and D are supported in the housing B, and providing a compartment 23 in the body portion between said walls 21 and 22, wherein the four 5 rotor units E and F, G and H are rotatably mounted on the shafts C and D, as will be subsequently described. As before mentioned the main body portion is open at the opposite side thereof, and along the marginal 10 edges at said sides, the body portion 20 is provided with the outwardly extending attaching flanges 25 and 26, adapted to detachably receive bolts 27 for the securing of end plates 30 and 31 over said open ends of 15 the compartment of the main body 20. Within said compartment 23 of the body 20 is disposed a transverse web 34 integral with the walls defining the body 20, located in a plane at right angles to the longitudinally 20 extending shafts C and D, and substantially midway between the open ends of the compartment 23, to divide the latter into the compartment 23^a wherein the rotor units E and G cooperate, and a second compartment 23^b wherein the rotor units F and H cooperate, as will be subsequently described. Of course, this web 34 is provided with suitable openings therethrough for receiving the 25 shafts C and D and other features of the improved device, as is well illustrated in Figure 1 of the drawings.

At diametrically opposed sides of the compartment of the main body 20 the latter is provided with upwardly sloping tubular extensions 36 and 37, having inlet ports or passageways 38 and 39 respectively therein, which slope downwardly from the outer ends of the extensions 36 and 37, for communication at the lower ends of said passageways 40 with the compartments 23^a and 23^b in the housing B, as is illustrated in Figures 3 and 6 of the drawings. As is illustrated in Figure 3 the web 34 at each side of the housing passes across the passageways 38 and 39, to 45 divide each of said passageways or ports immediately at the entrance of the same to the compartments 23^a and 23^b, so that the fluid medium entering the passageway 38, will be divided at 41 and 42 as illustrated in 50 Figure 3 of the drawings, for flow into the compartments 23^a and 23^b respectively, and likewise at the passageway 39 the web portion 34 divides the said passageway into portions 43 and 44 for the compartments 23^a and 23^b respectively. The upward slope of the passageways 38 and 39 from their communication with the compartment of the housing, as illustrated in Figure 6, provides 55 an important feature in connection with the trap of certain liquid medium therein, when such is being used as an operating medium or as a medium which is being operated upon, to permit the settlement of such liquid to cross the intermeshing zone of the rotors of 60 the upper and lower shafts, to obviate the 65

priming of the pump or compressor, so that the apparatus is always in condition for use without the necessity of priming with the desired medium.

The shafts C and D are horizontally supported in a parallel spaced relation in suitable anti-friction bearings 45 mounted in detachable brackets 46 and 47 at opposite ends of the housing B; said brackets 46 and 47 each being supported by top and bottom 70 arms 48 and 49 connected with the end plates 30 and 31 of the housing B, in the relation of details illustrated in Figure 1 of the drawings. The bracket arms 48 and 49 are preferably integral with the plates 30 and 31, 75 extending horizontally outwardly therefrom at the upper and lower ends of said plates 30 and 31, and the bracket members 46 and 47 are elongated and at their ends secured in detachable relation by screws or bolts 50 to 80 said arms 48 and 49. Each bracket member 46 and 47 supports a pair of the anti-friction bearings 45, which may be of the roller bearing or ball bearing as illustrated. Each of the bracket members 46 and 47 for the 85 accommodation of each anti-friction bearing 45 is recessed inwardly of its outer side to provide a bearing pocket 52 over which detachable closure caps 53 may be secured at the outer sides of the bracket members 46 in 90 order to seal the bearings within the pocket 52.

Each bearing 45 preferably comprises an outer race 56 mounted rather loosely in the pocket of the bracket member 46 or 47, as the case may be, and an inner race 57 snugly mounted on the respective shaft C or D; anti-friction members, such as balls 58 being placed between the said inner and outer races in order to support the ends of the 105 shafts C and D in an anti-friction relation with respect to the housing B, as can readily be understood from Figure 1 of the drawings.

It is preferred to adjust the shafts C and 110 D longitudinally in order to properly position the rotor units E, F, G and H, which are keyed with said shafts. To this end the shafts C and D immediately outwardly of the bearings 45 are screw threaded at 60, for adjustably receiving nuts 61 thereon, so that by adjustment of the nuts 61 against the inner races of the anti-friction bearing 45, the shafts C and D may be longitudinally adjusted in the housing, to the desired degree to best position the rotor units E, F, G and H, so that they will bear with the least frictional engagement with the housing B. The nuts 61 it should be noted are also located in the compartments which 115 enclose the bearings 45, so that the caps 53 must be removed in order to adjust the nuts 61 and consequently the shafts C and D.

The upper shaft C extends thru the upper portion of the compartment 23, on an 120

axis located above the inlet and outlet passageway portions 41 to 44 inclusive, and this shaft has rotatably keyed therewith the rotors E and F at opposite sides of the web portion 34 of the housing B, in a cooperative relation with a stationary supporting core 70.

The lower shaft D has rigid therewith the rotor units G and H, respectively disposed in the lower portions of the compartments 23^a and 23^b, and of course at opposite sides of the web 34; said rotor units respectively cooperating with cores 75 and 76 which are stationary with the housing B and located in the lower portions of the compartment 23^a and 23^b in the relation of parts to be subsequently described in detail.

Referring to the rotor units E and F which are carried by the shaft C in the upper parts of the compartment 23^a and 23^b respectively, each of said units is of the form illustrated in Figures 1 and 10 of the drawings, comprising a ring-shaped hub portion 80, having a passageway 81 therethrough for receiving the reduced end 82 of the shaft C; a key groove 83 being provided along the passageway 81 for receiving a key 84 by means of which to key the rotor unit upon the shaft C. At one end of the hub portion 80, the same is annularly flanged outwardly at 85 in an integral relation, and projecting from the opposite side of the flange 85 with respect to the hub 80 are provided segmental shaped vanes 86 and 87, in uniform circumferentially spaced relation about the axis of the rotor; said vanes 86 and 87 being preferably at exactly diametrically opposed locations with respect to the axis of rotation of the rotor unit; and the opposite edges 88 of said vanes 86 and 87 being disposed in planes radial with respect to the axis of rotation of the rotor unit, and as illustrated in Figure 6 of the drawings. It is to be noted that the said vanes 86 and 87 are of segmental form in cross section transversely of the axis of rotation, and each of said vanes being of uniform thickness at any location thereon, providing outer convex surfaces and inner concave surfaces, which are respectively adapted to cooperate in a sliding sealed relation upon the inside surfaces of the walls of the housing B and the exterior convex surface of the core 70.

The core 70 has been detailed in Figure 9 of the drawings, and the same comprises an elongated tube formed intermediate its ends with an annular integral flange 90, to divide the same into end tubular portions 91 and 92 at opposite sides of the said flange 90; the former being the longer. The web 34 in the upper portion of the compartment 23 is provided with an opening 93 therethrough and it is recessed at 94 inwardly of the side which faces the compartment

23^b, for receiving therein in a flush relation the attaching flange 90 of the supporting core 70, which is bolted in place to the housing B by means of bolts 100 secured to the web 34 as illustrated in Figure 1. The longer tubular portion 91 of course extends thru the opening 93 and projects into the upper portion of the compartment 23^a where the same extends between the vanes 86 and 87; the latter at their facing concaved sides preferably bearing on the portion 91 in a fluid sealed relation thereon. The shaft C of course extends thru the passageway 97 of the core 70. The portion 92 of the core 70 extends at the opposite side of the supporting web 34 from the core portion 91, and projects into the space between the vanes 86 and 87 of the rotor unit F; the vanes at their concave sides bearing on the portion 92 in a fluid sealed relation thereon.

An important feature in the placement of the rotor units E and F is the fact that their hubs 80 rotatably extend into openings 98 provided in the end plates or walls 30 and 31 of the housing B, and the outer sides of said hub portions 80 are thus exposed at the outer sides of the end walls 30 and 31, for receiving suitable sealing ring constructions 101 by means of which to seal the bearing juncture of the rotors E and F on the end walls 31 and 32, and which sealing ring constructions 101 will be subsequently described.

The provision of the hubs 80 at the opposite sides of the body portion 85 of the rotor units E and F from the vanes 86 and 87 enables a proper thickness of hub to be provided in a non-interfering relation with the vanes; the latter incident to such construction being placed as close together as possible, so that a very compact rotor unit is provided which may attain maximum efficiency without considerable bulk.

Spacing sleeves 105 are provided about the shaft ends 82 between the hubs 80 and the bearings 45 adjacent thereto.

The rotor unit G in the lower portion of the compartment 23^a is preferably integral with the shaft D, and includes an annular flange 106 rigid on the shaft, in sliding abutment against the side of the web 34 which faces the compartment 23^a; said flange 106 having diametrically opposed vanes 107 and 108 thereon, which in cross section transversely of the shaft are segmental in formation, and which are uniformly spaced circumferentially of the rotor for the same distance. These segments 107 and 108 are of the same formation as the vanes or segments 86 and 87, and preferably of the same thickness, having outer convex sides and inner concave sides respectively in sliding abutment with the inner walls of the housing B and the outer circumference of the supporting core

75 which is illustrated in Figure 12 of the drawings as a detail. It is to be thus noted that the shaft D really constitutes the hub portion for the rotor G, since the hub 109 of said rotor G is really rigid or integral with the shaft D.

The rotor H is detailed in Figure 11 of the drawings and comprises a substantially ring-shaped or disc-body portion 110, having a central opening 111 therein for receiving the shaft D therethrough; this disc portion 110 being adapted to abut up against the opposite side of the web 34 from the rotor unit G, and having openings 112 therein for receiving bolts 113 by means of which the said rotor unit H may be connected in the hub portion 109 of the rotor unit G, to rotate the rotor units G and H together upon rotation of the shaft D, as is readily apparent from Figure 1 of the drawings. The rotor unit H includes the segmental vanes 115 and 116, which are diametrically disposed in a uniformly spaced relation circumferentially of the rotor, and which have outer convex and inner concave facing surfaces.

As is illustrated in Figure 12 of the drawings, each of the supporting cores 75 and 76 includes a substantially cylindrical shaped portion 115^a, having a passageway 116^a therein, which receives the shaft D therethrough; this tubular portion 115^a at an end thereof being provided with a laterally extending segmental flange 118, adapted to abut against the inner side of the end wall 30 or 31, as the case may be; the flange 118 being provided with transverse openings 119 for receiving bolts or screws 120 by means of which the said supporting cores 75 and 76 are connected in a stationary relation with the housing B, in the lower portions of the compartments 23^a and 23^b respectively, so that the concaved surfaces of the vanes 107 and 108 of the rotor unit G slidably bear on the outer surface of the portion 115^a of the core 75, and the inner concave surfaces of the vanes 115 and 116 of the rotor H slidably bear on the outer circumference of the cylindrical portion 115^a of the core unit 76.

In referring to the cooperative relation of the rotor units E and G in the compartment 23^a, it is to be noted that the vanes of said units face in opposite directions from their respective hub portions, and the vanes of the rotor units E and G intermesh, that is, the vanes of the unit E enter the spaces between the vanes of the unit G during the rotation of said units, due to rotation of the shafts C and D. The vanes of said units E and G in arcuation are preferably 75° of a circle, more or less, so that it can be seen that during the rotation of the rotors in the compartment 23^a, the end surfaces of the vanes of the two rotors will

be spaced from each other, as is clearly evident from Figure 6 of the drawings.

The cylindrical shaped portion 91 of the supporting core 70 longitudinally at a side thereof is grooved or recessed at 120, to provide a concave surface, which is struck from a radius equal to the radius from the center of the rotor G to the outer convex surface of the vanes 107 or 108, and which cavity 120 inwardly of the outer convex surface of the tubular portion 91 of the core 70 is for the purpose of receiving the segmental vanes 107 and 108 of the rotor G therein during the rotation of the said rotors E and G in the compartment 23^a, to provide an effective seal during the rotation of said rotors. In similar manner the outer convex circumference of the cylindrical portion 115^a of the core member 75 is concavely recessed at 125 longitudinally thereof; the concave surface of this recess 125 being struck upon a radius which is equal to the radius from the center of the rotor E to the outer surface of one of the vanes 86 or 87 of the same, and so that the outer surfaces of said vanes 86 and 87 may slide over the concave surface of said recess 125 during the rotation of the rotors E and G, to provide an effective seal to prevent loss of fluids. By so recessing the core portions upon which the rotors E and G operate a surface seal is provided during the rotation of said rotors, which prevents communicating pressure between the entrance and exit ports of the housing B, and insures that the pumping or operating efficiency of the rotors is continuous and not intermittent.

The core portions 92 and 115^a of the supporting cores 70 and 76 are provided with longitudinal recesses or grooves 127 and 125 therein in manner similar to the grooves of the supporting cores as above described, for similar cooperation with the vanes of the rotor units F and H, for providing a fluid-tight seal between the entrance and exit ports of the compartments 23^b wherein said rotor units F and H operate in a cooperating relation.

It is to be noted that the end thrust due to the pumping of fluid will take place in both directions on each of the shafts C and D, due to the fact that each of said shafts supports a pair of the rotor units whose thrusts are in opposite directions along the shafts, and thus compensating and obviating the necessity of thrust bearings.

The principle of this invention in connection with only a pair of the meshing rotor units is preferably feasible, and the double provision of rotor units on each shaft may be dispensed with, since this is merely provided for a pump with large capacity, or considerable power, or in case where end thrust bearings need not be provided.

The shafts C and D are connected for 134

5 synchronous drive at the same speed by means of gears 130 and 131 keyed thereon; said gears being of the same size and in meshing relation at one end of the housing 10 exteriorly of the supporting bracket member 47. One of the shafts, such as the shaft C may be provided with a drive pulley 131^a, or analogous means to rotate the shaft D, and said shafts are rotated at the same rate 15 of speed due to the intermeshing gears 130 and 131, as is perfectly obvious.

At each outer side of the hubs 80 of the rotor units E and F, the special type of sealing ring construction 101 is provided, 15 which comprises a ring portion 135 bolted at 136 to the outer surface of each of the end walls 30 and 31, circumferentially about the shaft C; said ring portion 136 providing an inwardly facing annular flange 137, against 20 which the outwardly facing edge of a spring urged ring 138 engages. The spring urged ring 138 is of the formation illustrated in Figure 13 of the drawings, being reciprocably received within a suitable annular 25 groove formed inwardly of the outer surface of the end walls 30 and 31, concentric with the shaft C; said rings 138 having barrel shaped projections 140^a thereon with sockets 141^a therein opening only at the sides which 30 face the bottom of the grooves 144^a in which which the ring 138 is provided. In these 35 sockets 141^a compressed springs 145^a are provided, which at one end engage the end walls 30 or 31 as the case may be, and at the opposite end engaging against the end walls 40 provided by the sleeves 140^a of the ring 138, to force the latter outwardly into margin 45 abutting relation with the annular flange 137 which is rigid with the housing B. A pin 50 146^a, is keyed or rigid with the rotor E or F, as the case may be, and enters one of the sockets 141^a to cause a rotation of the sealing ring member 138 with the rotor. Due to the fact that the ring portion 135 is attached 55 at the outer side of the mounting of the hub 80, which has a sliding fit in the opening 98 of the end wall of the housing, and the ring portion 138 is at the opposite side of said mounting, leak of compression 60 past the bearing of the hub portions of the rotors E and F on the housing B is prevented.

In order to prevent leak of compression 55 along the shaft D outwardly beyond the ends of the rotors G and H and beyond the apertures in the walls 30 and 31 thru which the shaft D extends, sealing ring constructions 140 are provided, including non-rotary portions 141 reciprocably keyed in annular 60 grooves provided inwardly of the outer surfaces of the end walls 30 and 31; said ring portions 141 being spring urged and of the same general construction as the ring portions 138 above described, and at their outer 65 annular edges being urged into sealing en-

gagement with the annular edges of rings 145 which are keyed on the reduced ends 146 of the shaft D, at the outer side of the end walls 30 and 31. This sealing ring construction 140 thus seals the juncture thru 70 which the ends of the shaft D extends beyond the walls 30 and 31, and prevents leak of compression, as is quite obvious. Spacing sleeves 148 are extended between the ring portions 145 and the adjacent anti-friction 75 bearings 45, as is illustrated in Figure 1 of the drawings; said spacing sleeves being disposed about the reduced ends of the shaft D.

As to operation, if the passageway 38 is 80 used as an inlet, the rotors will operate as illustrated in Figures 4 and 5 of the drawings, to draw the medium thru the inlet port 38; the chisel edge of the web portion 34 which faces in the passageway 38 dividing the stream of the fluid so that it will flow into the passageway ports 41 and 42 into each of the chambers 23^a and 23^b, due to the operation of the intermeshing vanes of the 85 rotary units in each of said compartments 23^a and 23^b. It is to be noted that the width of the vanes are substantially smaller than the width of the spaces in which they mesh, so that the end surfaces of the intermeshing 90 vanes are in spaced relation and they may be flat, radial, or any shape desired, so that for the purpose of providing a seal between the inlet and outlet ports of the improved 95 pump or compressor, it is not important to have the end surfaces of the vanes of the 100 intermeshing rotors in sliding or any other engaging relation, and this is very important, since very often foreign materials have a tendency to pass thru the mechanism 105 and if the end surfaces of the vanes are in abutting relation, the foreign materials, very often metal, will cause a wedging and possibly breaking of the parts of the rotors, and even parts of the housing.

The vanes of the rotor units fit snugly 110 against the adjacent stationary parts of the housing B and cores at the centers of said rotor units, and the said rotor vanes due to the cooperation of the same on the cores of the complement rotor, do not meet any other 115 sealing gaskets or means, since surface sealing contact is effected at all times between the inlet and outlet ports, yet the spaced intermeshing of the vanes permits of an 120 efficient draft thru the chambers of the housing, for sucking air or other fluid medium from the intake for discharge thru the exit port.

The fact that the rotor units of the shaft 125 D are assembled to a common disc with vanes facing in opposed directions, and as the complement double rotor of the shaft C has the vanes facing in the same direction, a very compact rotor construction for the improved device is provided, which tends towards com-

pactness and efficiency in operation, as well as ease of assemblage and disassemblage of parts.

The improved mechanism is very durably 5 constructed, without delicate parts, to serve as a prime mover, pump, compressor or the like, and the same is ideal for the pumping of fluids of great viscosity.

The fact that the vanes of the rotors are 10 equi-distant and circumferentially spaced about the hub or body portion of the rotor insures that the rotor will be effectively balanced both statically and dynamically, during rotation, doing away with all eccentric 15 tendencies which are apt to cause vibration and leak of the fluid operating or being operated upon. The places where leakage is to be expected between the housing or stationary parts and revolving parts are equipped 20 with the special seal rings which are preferably made of metal or other material to provide an efficient seal, and these rings have a spring take up arrangement to compensate for wear. Whatever compression 25 does leak past the vanes, in the nature of air, gas or liquid, will pass thru suitable conduits 150, which are connected with ducts which communicate with the spaces nearest to the seal rings; said conduits being connected 30 at their opposite ends with the suction passageway of the improved device, to prevent loss of the medium being operated upon.

The fact that the vanes are not in contact 35 obviates the requirement of machining the same, nor does any fine adjustment of rotors have to be effected.

The fact that the end brackets 46 and 47 are detachable, enables all parts of the 40 mechanism to be readily detachable from opposite ends of the housing B, as is readily apparent.

For minor longitudinal adjustments of the shafts C and D, clearances of from three 45 to six thousandths of an inch may be provided between the housing and end surfaces of the rotor. The bearing caps 53 are provided with annular pilot rings 53^a which bear against the outer edges of the outer 50 races of the ball bearing to hold the shafts and rotors against axial movement. It is apparent that by adjusting the bearing cap 53, which may have some clearance with respect to the adjustment bracket of the 55 housing, the outer races may be adjusted to take up any end play of the shaft and to properly adjust the same with respect to the housing and rotors.

Various changes in the shape, size, and 60 arrangement of parts may be made to the form of invention herein shown and described, without departing from the spirit of the invention or the scope of the claims.

I claim:

65 1. In a device of the class described the

combination of a housing having a compartment therein provided with inlet and exit ports, a pair of shafts rotatably mounted on the housing to extend thru said compartment, individual stationary cores carried by 70 the housing concentrically about each of said shafts and within said compartment, and a rotor keyed for rotation with each of said shafts, each of said rotors including a plurality of vanes, with the vanes of one rotor 75 in a complementary intermeshing relation with the vanes of the other rotor, the outer surfaces of the vanes and the cores being formed to provide a sealing surface contact between the intake and exhaust ports during 80 rotation of said rotor.

2. In a device of the class described the combination of a housing having a compartment therein, a plurality of shafts rotatably supported by the housing extending thru the compartment, said housing having intake and exhaust ports to the compartment, a stationary substantially cylindrical shaped core carried by the housing about each of said shafts and extending transversely across said compartment, each of said cores having a grooved depression inwardly thereof facing the other shaft core, the said groove depressions being disposed transversely of the compartments and being 90 arcuated so that the center of arcuation of the depressions of each of said cores is concentric with the shaft on which the other core is mounted, and rotor units 95 rotatably supported in the housing with vanes extending into said compartment in a fluid sealed relation, the vanes of one unit being adapted to alternate with the vanes of the other rotor during rotation of said rotors and the outer surfaces of the vanes being 100 convex and adapted to slidably pass through the depressions of said cores during rotation to provide a fluid seal between the intake and exhaust ports.

3. In a device of the class described the combination of a housing having a compartment therein, a plurality of shafts rotatably supported by the housing extending thru the compartment, said housing having inlet and outlet ports to the compartment, stationary substantially cylindrical shaped cores carried by the housing about each of said shafts and extending transversely across said compartment, each of said cores having a grooved depression inwardly thereof facing the other shaft core, the said groove depressions being disposed transversely of the compartments and being 110 arcuated so that the center of arcuation of the depressions of each of said cores is concentric with the shaft on which the other core is mounted, and rotor units rotatably supported in the housing each having a pair of spaced vanes extending into said compartment in a fluid sealed relation, the vanes 115 120 125 130

- of each unit being adapted to alternate in non-engaging relation with the vanes of the other rotor during rotation of said rotors, the outer surfaces of the vanes being convex and adapted to slidably pass through the depressions of said cores during rotation to provide a fluid seal between the inlet and outlet ports.
4. In a rotary device of the class described the combination of a housing having a pair of compartments therein, and inlet and outlet port openings for each compartment, a pair of shafts rotatably supported by the housing extending thru each of said compartments, in a spaced relation, a rotor mounted on each shaft in each compartment, the rotors of the shafts in each compartment having vanes thereon of substantially segmental formation and adapted to alternate in a meshing non-engaging relation during rotation of the same in their compartment to create a suction in the compartment for drawing fluid from the inlet port and discharging it through the outlet port, the rotors of each shaft having the vanes thereof positioned to place the end thrusts on the shaft in opposed directions to counter balance any end thrusts upon said shafts.
5. In a rotary device of the class described the combination of a housing having a pair of compartments therein and inlet and outlet port means for each compartment, a pair of shafts rotatably supported by the housing extending thru each of said compartments, in a spaced relation, a rotor mounted on each shaft in each compartment, the rotors of the shafts in each compartment having vanes thereon of substantially segmental formation and adapted to alternate in a meshing non-engaging relation during rotation of the same in their compartment to create a suction in the compartment for drawing fluid from the inlet port means and discharging it through the outlet port means, the rotors of each shaft having the vanes thereof positioned to place the end thrusts on the shaft in opposed directions to counter balance any end thrusts upon said shaft, and anti-friction means rotatably supporting said shafts in said housing for longitudinal adjustment to move the rotors to a predetermined extent across their respective compartments.
6. In a rotary device of the class described the combination of a housing having a compartment therein, and inlet and outlet port means to the compartment, a shaft rotatably supported in the housing having means to longitudinally adjust the shaft across the compartment, a rotor keyed on the shaft at an end of the compartment having segmental shaped vanes extending into the compartment, a second shaft, means mounting the second shaft in the housing for longitudinal adjustment thru the compartment, a rotor mounted on said second shaft having vanes laterally extending therefrom of segmental formation adapted to intermesh in the spaces between the vanes of the other rotor during rotation of said shafts and rotors, the vanes being so positioned that they face in opposite directions from their respective locations of attachment upon their shafts.
7. In a rotary device of the class described a housing having a compartment therein and inlet and outlet ports to the compartment, a pair of shafts, means rotatably mounting said shafts on the housing for substantially parallel extension thru said compartment, rotors keyed upon each of the shafts, each of the rotors having a hub portion and spaced vanes extending from a side of the hub portion substantially parallel with the respective shafts, the vanes of one rotor being adapted to enter between the spaces of the vanes of the other rotor during rotation of said rotors, means carried by the housing cooperating about the shaft and with the vanes of said rotors to establish a surface seal between the inlet and outlet ports, a liquid seal ring construction carried by the housing and one of said rotors to prevent leak of fluid past the connection between said rotor and the housing, and a liquid seal ring construction carried by the shaft of the other rotor and the housing to prevent leak of fluid from the compartment past the ends of said rotors and shafts.
8. In a rotary pump the combination of a supporting housing having a compartment therein and inlet and outlet ports to the compartment, a pair of shafts rotatably supported by the housing extending thru the compartment, a pair of rotors keyed on each of the shafts in the compartment, the said rotors of each shaft having segmental shaped vanes extending in opposite directions longitudinally of the shaft from the connections of said rotors on the shafts, the rotors and vanes being so positioned that the vanes of the rotors of one shaft alternate in the spaces between the vanes of the rotors of the other shaft during rotation of said shafts, and means cooperating with said rotors and the vanes thereof to provide a fluid seal between the inlet and outlet ports upon rotation of the rotors and shafts.
9. In a rotary pump of the class described the combination of a supporting housing having a compartment therein and inlet and outlet port means therefor, shafts rotatably supported by the housing and extending into said compartment, rotors keyed on each of the shafts in a rotary relation within the compartment of the housing, each of said rotors including vanes with the vanes of one shaft alternating in the spaces between the vanes of the rotor of another shaft, and seal rings supported by the housing and the shafts.

tary parts of the shaft and rotor to prevent leak of fluid pressure from the compartment.

10. In a rotary pump of the class described the combination of a supporting housing having a compartment therein and inlet and outlet port means therefor, shafts rotatably supported by the housing and extending into said compartment, rotors keyed on each of the shafts in a rotary relation within the compartment of the housing, each of said rotors including vanes with the vanes of one shaft alternating in the spaces between the vanes of the rotor of another shaft, seal rings supported by the housing and the rotary parts of the shaft and rotor to prevent leak of fluid pressure from the compartment, and spring means cooperating with said seal rings to normally maintain them effective and to compensate for wear thereon.

11. In a rotary pump the combination of a housing having a compartment therein and inlet and outlet ports, a pair of shafts rotatably supported by the housing extending into the compartment thereof, rotors rotatably supported by the housing and shafts having spaced vanes thereon with the vanes of one rotor of one shaft cooperating in the space between the vanes of the rotor of the other shaft, the vanes being so disposed that during rotation of the rotors they will create a suction in the compartment for drawing fluid from the inlet port and passing it throughout the outlet port of the compartment, and sealing means at the juncture of the rotary parts of the rotors and shafts with the stationary parts of the housing, each of said sealing means comprising a stationary ring carried by a stationary part of the housing and a rotary ring keyed to the rotary part of the housing, and spring means cooperating to force the said stationary and rotary rings of the sealing means into a sealing engagement at all times.

12. In a rotary pump the combination of a housing having a compartment therein and intake and discharge passageways communicating intermediate the upper and lower ends of the compartment, said passageways sloping from their communication with the compartment in a direction upwardly to the outer ends of said passageways remote from the compartment, whereby to provide inlet and outlet ports in substantially horizontal alignment intermediate the upper and lower ends of said compartment, a pair of shafts rotatably carried by the housing in superposed relation across said compartment, a rotor rotatably carried by one shaft in the

upper part of the compartment a rotor carried by the other shaft in the lower part of the compartment, said rotors each including spaced vanes with the vanes of one rotor arranged in the spaces between the vanes of the other rotor during rotation of said shafts, the location of mesh of the vanes being in alignment with inlet and outlet communication of the ports with the compartment.

13. In a rotary pump the combination of a housing including a body portion having a compartment therein open at the ends of the body portion of the housing, a web transversely extending thru the compartment of the body portion between the open ends of the said body portion to subdivide the compartment into a pair of chambers at opposite sides of said web, cover plates detachably mounted over the open ends of the compartment to enclose the chambers, shafts rotatably supported by said cover plates in an anti-friction relation in substantially parallel relation to each other transversely extending thru each of said chambers, a pair of rotors rotatably carried by one of said shafts each including a hub portion keyed to the shaft at a location within the area of the cover plates, said rotors having vanes extending from said cover plates inwardly into the upper portions of the chambers of the housing, a stationary tubular core carried by the housing web providing cylindrical shaped tubular portions extending into each of the chambers at opposite sides of said web into the central spaces between the vanes of the above mentioned rotors, each of said cylindrical shaped portions of the core having longitudinal grooves therein, a pair of rotors connected to the other shaft at the web of the body portion of the housing and having spaced vanes extending in opposite directions from said web into each of the chambers of said body portion of the housing, cores connected with the cover plates each including cylindrical portions extending about the last mentioned shaft in each of the chambers between the vanes of the last mentioned rotors, the rotor vanes of one of the shafts being positioned in spaced relation so that the same will enter into the spaces between the vanes of the rotors of the other shaft during rotation of said shafts, last mentioned cores having longitudinal grooves therein, and the vanes of each of the shafts being adapted to slide in a surface and fluid sealing relation across the grooves of the cores of the other shaft during rotation of said rotors and shafts.

VAINO W. MALMSTROM.
